UNITED STATES PATENT OFFICE

HUGH HARLEY CANNON AND WRIGHT W. GARY, OF LOS ANGELES, CALIFORNIA,
ASSIGNORS, BY MESNE ASSIGNMENTS, TO CANNON-PRUTZMAN TREATING PROC-
ESSES, LTD., OF LOS ANGELES, CALIFORNIA, A CORPORATION OF CALIFORNIA

METHOD OF SWEETENING SULPHUROUS PETROLEUMS

No Drawing.

Application filed January 21, 1929. Serial No. 334,004.

An object of our invention is to provide a reagent and a method for converting the mercaptans or alkyl hydrosulfids which occur in petroleum distillates into the corresponding alkyl disulfids.

5 A further object of our invention is to provide such a reagent which is at once cheaper and more effective than the reagents heretofore used for this purpose.

10 A further object of our invention is to provide a reagent which is suited for application to the oil in the form of a substantially dry powder.

15 The hydrosulfids or mercaptans, having the general formula RSH, are found in the distillates from almost all sulfur containing petroleums. The members of this group are chemically unstable, actively attack copper and brass and have a most objectionable 20 odor. They are therefore highly undesirable constituents of commercial gasoline.

The well known process of "sweetening" consists in converting the mercaptans into the corresponding disulfids, bodies which 25 are stable, noncorrosive and of a mild odor. As ordinarily practiced this conversion is effected in two steps. In the first the oil is treated with an aqueous solution of lead 30 oxid (litharge) in caustic soda, this solution containing the hypothetical "sodium plumbite," a body which has not hitherto been prepared in the dry form. By this solution the mercaptans are converted into lead salts, the so-called lead mercaptids which separate 35 only slowly and incompletely from the oil. In the second step the lead salts are decomposed by the addition of free sulfur, the lead being precipitated as a sulfid while the two alkyl-sulfur radicles previously attached to 40 the lead conjoin to form the dialkyl-disulfid. The reactions which are believed to take place are as follows:

All the sulfur originally present in the mercaptan is also found in the disulfid and 50 the process is therefore not one of desul-

furization but is merely the conversion of a compound having deleterious properties into one which is relatively innocuous. It will be understood that the above remarks apply to the prior art.

55 We have discovered that a lead salt of any of the alkali earth metals, and particularly a lead salt of calcium, may be prepared in a form suitable for use in the above described sweetening process, and 60 that these salts have manifold advantages over the sodium salt heretofore used. The earth metal salts are much cheaper than the sodium salt; they are very readily prepared; they are not caustic in handling and 65 do not corrode metals nor creep nor absorb carbon dioxid, and they may be prepared in the form of dry powders and are fully effective in such form. Because of this property they may be filtered out of the 70 treated oil, reducing sludge losses to a minimum.

75 Other comparisons are: that the sodium salt has a powerful action on the oil other than the desired converting action, forming water-soluble salts with phenols, naphthenic acids and unsaturated hydrocarbons, these salts rapidly accumulating in the solution if an attempt is made to use it repeatedly. The alkali earth metal salts are inert in 80 this respect and do not load up with organic matter if reused. The sodium salt promotes the formation of undesirable and dark colored gums in sour, unstable oils, while the earth metal salts do not. The sodium salt 85 when repeatedly used, has been found to have a strong tendency toward oxidation to sodium sulfate in the presence of lead sulfid and air, while the earth metal salts have no such tendency. Finally, the spent earth 90 metal reagent may be regenerated and brought back to its original efficiency by a simple and cheap manipulation.

We prepare our new reagent in the following manner, using lime (calcium hydr- 95 oxid) as an example of any alkali earth hydroxid. With any desired quantity of commercial litharge we admix a suitable proportion of commercial hydrated lime and, after thorough blending, add sufficient 100

water to produce a thick paste or cream. From this the excess water may be removed by filtering. The water required to produce the reaction is only that required to dampen the mass and, if preferred, only this quantity may be added, thus avoiding the filtration. The water, however, must be completely disseminated throughout the mass, a somewhat difficult matter unless some sort 10 of pugging apparatus is available.

The damp mass is then dried in any convenient manner to such consistency that it may be finely pulverized. It may contain fifteen percent by weight of water or even 15 more, or it may be rendered completely dry, without any appreciable effect on its activity as a reagent, and it may be dried at any temperature up to at least 300° F. and probably at even higher temperatures.

20 The preferred proportion of alkali earth metal hydroxid to lead oxid for the above mixture is indicated by the following relations:

$$25 \quad \begin{aligned} \text{Ca(OH)}_2 : \text{PbO} &:: 74:223 \\ \text{Ba(OH)}_2 : \text{PbO} &:: 172:223 \\ \text{Sr(OH)}_2 : \text{PbO} &:: 122:223 \end{aligned}$$

As the lead oxid is the more expensive of the two constituents it is desirable to use 30 a small excess of the hydroxid, up to say ten percent over the calculated quantity (though even a much greater excess is entirely harmless), and the water contents as well as any carbonate found in the alkali earth metal hydrate should be allowed for in the calculation.

The first step in the treatment of oil containing mercaptans is to thoroughly intermix with the oil a sufficient quantity of the 40 above reagent to convert the mercaptans into lead mercaptids. If the quantity of sulfur present in the oil in the form of mercaptans is known the theoretical quantity of lead is shown by the relation

$$45 \quad \text{S}_2 : \text{Pb} :: 64:207.$$

An excess of not less than ten percent over the calculated quantity of lead should be allowed to ensure completion of the conversion. If the quantity of mercaptan sulfur is not known the oil should be dosed with small quantities of the reagent until it indicates "sweet" to the well known "doctor test". An excess of reagent is harmless except as it is wasteful.

The spent reagent may now be settled and withdrawn as a sludge or the next step may be carried out without removing it. This step consists in cautiously adding finely pulverized free sulfur until all the lead is precipitated as lead sulfid. Even a slight excess of sulfur will render the oil corrosive to metals and should be avoided. If the quantity of mercaptan sulfur is known 60 the dose of free sulfur to be added will be

just one half the mercaptan sulfur, as will be evident from the reactions below. If this quantity is not known the free sulfur should be added in small doses with constant agitation until a sample of the oil, 70 filtered to remove sediment, shows no black or brownish discoloration when treated with a pinch of free sulfur.

We are uncertain as to whether it is more desirable to proceed to the second step without removal of the excess of reagent or after its removal. It is simpler operation to leave it suspended in the oil and to proceed at once to the precipitation with sulfur. On the other hand it appears that when this procedure is followed there is some reaction between the sulfur and the necessary remainder of unused chemical, causing a loss of both reagent and sulfur and making the determination of the end point for sulfur addition somewhat uncertain, with danger of over-addition and the consequent production of a corrosive oil. Apparently a slight gain in economy and certainty must be balanced against an added convenience, 80 with no material advantage on either side.

The reactions occurring in the preparation of the reagent and in the treatment of the oil we believe to be as follows, though we would not be understood as limiting ourselves thereto:

As a final step the spent reagents, which will be found as a dry powder suspended in the oil, may be allowed to settle and the clear oil decanted, or preferably the oil may be filtered through cloth and the sediment thus removed completely. If the above instructions have been followed the most refractory oil will now be found to be completely sweetened, the mercaptans being entirely converted into the corresponding disulfids.

It will be understood that the sweetening result produced in the manner above described will not be obtained if the two constituents of the reagent mixture be separately applied to the oil, as neither the alkali metal hydroxid nor the lead monoxid has any material sweetening effect. The sweetening effect is due to the joint action of the two agents and is probably due to the formation of a compound, as for instance the hypothetical calcium plumbite, between the lime and the lead. So far as we know the existence of this or of any definite compound cannot be positively proven, and in the appended claims we lay claim to the ingredients of the reagent without assuming either that they do or that they do not enter into combination.

We claim as our invention:

1. The method of converting mercaptans into lead mercaptids, comprising: treating a liquid containing said mercaptans with a powdered solid comprising lead monoxid and a hydroxid of an alkali earth metal.
2. The method of converting mercaptans into lead mercaptids, comprising: treating a liquid containing said mercaptans with a powdered solid comprising lead monoxid and calcium hydroxid.
3. The method of sweetening oils containing mercaptans, comprising: treating said oils with a powdered solid comprising an alkali earth metal hydroxid and lead monoxid to convert the mercaptans into lead mercaptids and thereafter precipitating the lead from said mercaptids.
4. The method of sweetening oils containing mercaptans, comprising: treating said oils with a powdered solid comprising an alkali earth metal hydroxid and lead monoxid to convert the mercaptans into lead mercaptids and thereafter precipitating the lead from said mercaptids by the addition of sulfur to said oil.
5. The method of sweetening oils containing mercaptans, comprising: treating said oils with a powdered solid comprising calcium hydroxid and lead monoxid, to convert the mercaptans into lead mercaptids and thereafter precipitating the lead from said mercaptids by the addition of sulfur to said oil.
6. The method of sweetening oils containing mercaptans, comprising: treating said oils with a powdered solid comprising calcium hydroxid and lead monoxid, to convert the mercaptans into lead mercaptids and thereafter precipitating the lead from said mercaptids.

In witness that we claim the foregoing we have hereunto subscribed our names this 31st day of December, 1928.

HUGH HARLEY CANNON.
WRIGHT W. GARY.
